UNITED STATES PATENT OFFICE.

EDWARD B. ALLEN, OF NEWTOWN, CONNECTICUT, ASSIGNOR TO THE SINGER MANUFACTURING COMPANY, OF ELIZABETH, NEW JERSEY, A CORPORATION OF NEW JERSEY.

WORK-CLAMPING MECHANISM FOR SEWING MACHINES.

Application filed April 13, 1926. Serial No. 101,682.

This invention relates to sewing machines more particularly of the type having relatively movable stitch-forming and work-clamping devices and adapted to sew a group 5 of stitches and then come to rest. Machines of this type commonly have a needle-throat member, and the work-clamp includes upper and lower clamping means, of which the lower has an opening for the needle-throat member permitting the work-clamp and needle-throat member to be relatively shifted, not only during the sewing, but also out of and into sewing relation. In a sewing machine of the buttonhole type, for example, 10 the work-clamp and needle-throat member are shifted out of sewing relation to allow the buttonhole cutter to act upon the work. The needle-throat opening or clearance slot customarily provided in the lower work- 15 clamping means to permit the needle-throat member and work-clamp to be shifted out of sewing relation constitutes a gap in the lower clamping means preventing clamping of the work on all sides or all around the 20 area exposed by the work-clamp to the action of the stitch-forming mechanism. Hence there is liability that the work will be pulled and distorted by the action of the stitch-forming mechanism, particularly when 25 sewing adjacent the gap on the side of the stitched figure where the work is not clamped.

The present invention therefore has for an object to provide, in a machine of the 30 class described, for the clamping of the work on all sides or substantially all around the area exposed to the action of the stitch-forming mechanism, without blocking the relative movement of the work-clamp and 35 needle-throat member out of and into sewing relation.

To this end there are provided auxiliary 40 lower clamping means arranged to fill the gap in the effective work-clamping portions of the lower clamping means occasioned by the needle-throat clearance slot, said auxiliary lower clamping means being 45 displaceable from work-clamping position so as not to block relative movement of the 50 work-clamp and needle-throat member between sewing periods. Preferably the auxiliary lower clamping means are in the form of one or more levers pivotally supported on

the main lower clamping means or plates, so as to be shiftable horizontally out of and 55 into co-operative work-clamping relation with the upper clamping means or feet.

The invention will be more fully understood by reference to the following detailed description of two specific embodiments 60 thereof, accompanied by drawings in which Fig. 1 is a side elevation of a buttonhole sewing machine embodying one form of the invention. Fig. 2 is a fragmentary vertical section of the parts adjacent the sewing 65 point taken longitudinally of the machine bed and showing the work-clamp and needle-throat member moved out of sewing relation. Fig. 3 is a similar view of the parts after sewing relation thereof is restored. 70 Fig. 4 is a bottom plan view of the upper work-clamping feet. Fig. 5 is a plan view of the lower work-clamping means and needle-throat member in sewing relation. Fig. 6 is a similar view of these parts out 75 of sewing relation. Fig. 7 is a sectional view on the line 7-7, Fig. 5. Fig. 8 is a plan view of a modified form of the invention with the parts in sewing relation. Fig. 9 is a similar view with the parts out 80 of sewing relation, and Fig. 10 is a fragmentary vertical section of the parts in the position shown in Fig. 9.

This invention is shown as embodied in a 85 sewing machine of the buttonhole type designed for sewing circular eyelets and constructed substantially in accordance with the disclosure of my Patent No. 1,346,102, of July 13, 1920. Such a machine is constructed with a frame including the hollow rectangular bed 1, standard 2 and overhanging arm 3 terminating in the head 4. The stitch-forming mechanism is of the type employing 90 an upper straight reciprocating depth-stitch needle 5 and a lower curved slit-stitch 95 needle 6 with suitable driving mechanism such as disclosed in my Patent No. 1,162,207, of Nov. 30, 1915. The lower needle 6 is carried by the usual rotary turret 7.

The work-clamp comprises the usual lower 100 clamping plates 8, 8, and upper clamping feet 9, 9; the feet 9 being carried by the clamping arms 10 fulcrumed at 11 on blocks, one of which is shown at 12, mounted on the lower clamping plates 8. The clamps are 105 closed by depression of an arm 13 fixed to

the rock-shaft section 14 having a cam-member 15 which depresses the upper clamp-arm 10 to force the corresponding foot 9 into clamping engagement with the work. A 5 work-clamp of this nature is disclosed, for example, in my Patent No. 1,379,894, of May 31, 1921. The work-clamp is moved over the bed 1 during the sewing by the usual connections with the feed-wheel 16. Turning 10 movements are also imparted to the turret 7 and needle-bar 5' by the usual connections with the feed-wheel 16.

The buttonhole cutting mechanism is constructed substantially in accordance with the 15 disclosure of my Patent No. 1,048,786, of Dec. 31, 1912, and comprises the buttonhole cutter-levers 17, 18, fulcrumed at 19 on the travelling fulcrum-block 20. The tails of the cutter-levers 17, 18, are engaged by the 20 cutter closing cams 21, 22, on the cutter-shaft 23 which in the present machine is given a single rotation prior to sewing by means of the usual one-rotation clutch device. The cutter-fulcrum block 20 has travelling 25 movements imparted to it by the usual link connection 24 having a follower 25 entering the cutter advancing and retracting cam 26 on the cutter-shaft 23. The cutter-lever 18 carries the round eye cutter 27 30 which coacts with the flat brass or anvil 28 on the lever 17. The period of action of the stitch-forming mechanism is controlled by the usual stop-motion device 29 which establishes and interrupts driving relation 35 between the constantly running pulley 30 and the sewing shaft 31.

The sewing needles 5 and 6 are both reciprocated to pass loops of thread through or across the plane of the work. These 40 needles pass through the crescent-shaped aperture 32 in the usual needle-throat member 33 which is normally in engagement with the under surface of the work, Fig. 3, exposed by the aperture 34 in the lower 45 clamp-plates 8. The upper clamping feet are apertured at 35, Fig. 4, to expose an area of the upper surface of the work to the action of the stitch-forming mechanism. The aperture 34 in the lower clamp-plates 50 thus permits the needle-throat member to engage the work and support the work against the thrust of the upper needle 5.

During the buttonhole cutting operation the needle-throat member 33 must be gotten 55 out of the way of the anvil member 28. To this end it is mounted on a lever 36 fulcrumed at 37 on the turret 7. When the cutter-levers are advanced to cutting position an arm 38 on the lower cutter-lever 17 engages 60 the shank of the needle-throat member 33 and tilts the lever 36 forwardly, as shown in Fig. 2, thus displacing the needle-throat member 33 from the aperture 34 in the lower clamp-plates longitudinally of the 65 needle-throat clearance slot 39 in such clamp-

plates. This tilting throat-plate expedient is old and well known, being disclosed, for example, in my said Patents Nos. 1,048,786 and 1,162,207.

The necessity of providing the lower 70 clamp-plates with an opening leading away from the needle-throat aperture in such plates, to permit of a relative shift of the work-clamp and needle-throat member, as when cutting a buttonhole, has heretofore 75 prevented the clamping of the work on all sides of or all around the area exposed to the action of the stitch-forming mechanism, as there has heretofore been nothing below the work in this opening to support the 80 work against the pressure of the upper clamping feet. Hence there has been a tendency for the work to draw inwardly and become distorted in the vicinity of this gap or unclamped portion. 85

According to the embodiment of the present improvement illustrated in Figs. 1 to 7, inclusive, an auxiliary lower work-clamping element 40 is disposed in the opening or slot 34 in work-clamping relation with the upper clamping feet 9, when the needle-throat member 33 and work-clamp are in sewing relation, Fig. 3. The auxiliary lower work-clamping element 40 is formed as the L-shaped end of a lever 41 fulcrumed at 42 in a depression in one of the lower clamp-plates 8, Figs. 5 and 6, the tail of the lever 41 being acted upon by the spring 43 to yieldingly urge the clamping element 40 to work-clamping position, Fig. 5, with the pin 44 depending from the element 40 resting against the front edge of the needle-throat member 33. 100

When the cutter-levers are shifted forwardly preparatory to cutting the button-hole or eyelet-hole, the needle-throat member 33 which is shifted along the slot 39 pushes against the pin 44 and displaces the auxiliary clamping member 40 longitudinally of such slot to the position shown in 110 Figs. 2 and 6. When the cutter-levers are retracted, the spring 43 restores the auxiliary clamping member 40 to work-clamping position, Figs. 3 and 5. Thus the area of the work exposed to the action of the stitch-forming mechanism is securely clamped on all sides and distortion of the stitched figure is prevented. 115

According to the modified embodiment of the invention illustrated in Figs. 8, 9 and 10, the needle-throat clearance opening or slot 39 has been widened considerably at 39', 39" to receive the work-clamping extremities 45, of a pair of auxiliary lower work-clamping elements in the form of levers 46, pivoted at 47 on the respective lower clamp-plates 8. Springs 48 serve to yieldingly hold the levers 46 in work-clamping position, Fig. 8. Stop pins 49 in the respective lower clamp-plates 8 adjacent their meeting edges limit the 125 130 135

motion of the levers 46 under the influence of the springs 48. The meeting corners of the working ends 45 of the levers 46 are beveled off or slanted at 50 so as to meet the 5 semicircular needle-throat working clearance 51 in the lower clamp-plates 8 and form a complete lower work-clamping surface on all sides or all around the sewing position of the needle-throat member 33. When the work- 10 clamp and needle-throat member are relatively shifted out of sewing relation, as when the cutter levers 17, 18 advance and tilt the needle-throat member 33 about its pivotal support 37, the side portions of the circular 15 edge of the member 33 engage the inclined edges 50 of the levers 46 and spread such levers, as shown in Fig. 9, thereby affording clearance for the relative horizontal displacement of the needle-throat member 33 and 20 work-clamp.

The work-clamp may be opened and closed manually by shifting the finger-lever 13' on the rock-shaft section 14. In the present machine the clamp is closed automatically 25 during the advance of the cutter-levers preparatory to cutting the buttonhole. The lower cutter-lever 17 has mounted on the side thereof a roll 17^a which rides over the hump 17^b on the lever 17^c pivoted at 17^d on 30 the standard 2 and depresses such lever causing its downwardly curved free end 17^e to depress the lever 13 previously described. This mechanism is substantially the same as 35 that described in my said Patent No. 1,379,894.

The invention is not to be understood as limited to the particular type of sewing machine shown and described or to the particular details of construction and arrangement 40 of parts in the embodiments disclosed. So far as I am aware I am the first to provide a sewing machine with a work-clamp having upper and lower clamping means for clamping the work all around the area exposed 45 to the action of the stitch-forming mechanism with provision for relatively shifting out of and into sewing relation the work-clamp and an element which operates in the work-exposing aperture of a clamping element of the work-clamp during the 50 sewing. A thin cover-plate 45^a is preferably provided to cover all of the lever 41 except the work clamping extremity thereof. Suitable thin sheet metal covers 45^b are 55 preferably used to cover the springs 48 and the shanks of the levers 46, the working extremities 45 being exposed.

Having thus set forth the nature of the invention, what I claim herein is:

60 1. A sewing machine having, in combination, stitch-forming mechanism, a work-clamp including co-acting upper and lower work-clamping means apertured to expose an area of the work to the action of the 65 stitch-forming mechanism, an element op-

erating in the work-exposing aperture of one of said clamping means during the sewing, said one of said clamping means having a clearance opening leading from its work-exposing aperture to permit the work-clamp 70 and said element to be relatively shifted, said work-clamp also including an auxiliary clamping element disposed in said opening and displaceable from work-clamping position 75 therein.

2. A sewing machine having, in combination, stitch-forming mechanism, a needle-throat member, a work-clamp including co-acting upper and lower work-clamping means, the lower work-clamping means having a clearance opening for the needle-throat member, means for relatively shifting the needle-throat member and work-clamp horizontally out of and into sewing relation, said work-clamp also including auxiliary 80 lower work-clamping means disposed in said opening and displaceable from work-clamping position in said opening.

3. A sewing machine having, in combination, stitch-forming mechanism, a needle-throat member, a work-clamp including co-acting upper and lower work-clamping means, the lower work-clamping means having a clearance opening for the needle-throat member, means for relatively shifting the 90 needle-throat member and work-clamp out of and into sewing relation, said work-clamp also including auxiliary lower work-clamping means disposed in said opening, and automatic means for displacing said auxiliary work-clamping means from work-clamping position in said opening when the needle-throat member and work-clamp are 95 relatively shifted out of sewing relation.

4. A sewing-machine having, in combination, stitch-forming mechanism, a needle-throat member, a work-clamp including co-acting upper and lower work-clamping means, the lower work-clamping means having a clearance opening for the needle-throat member, means for relatively shifting the needle-throat member and work-clamp out of and into sewing relation, said work-clamp also including auxiliary lower 100 work-clamping means disposed in said opening, and automatic means for displacing said auxiliary work-clamping means from work-clamping position in said opening and for returning it to such work-clamping position 105 when the needle-throat member and work-clamp are relatively shifted out of and restored to sewing relation.

5. A sewing machine of the buttonhole type having, in combination, stitch-forming mechanism, a work-clamp having co-acting 110 upper and lower clamping means apertured to expose an area of the work to the action of the stitch-forming mechanism, a needle-throat member disposed, when in sewing position, in the aperture of the lower clamping 115

means, buttonhole cutting mechanism, means for relatively moving the work-clamp and needle-throat member out of sewing relation to expose the work to the action of the buttonhole cutting mechanism, said lower clamping means having a needle-throat clearance opening leading from said work-exposing aperture to permit of said relative movement, and auxiliary lower work-clamping means displaceably disposed in said opening.

6. A sewing machine of the buttonhole type having, in combination, stitch-forming mechanism, a work-clamp having coacting upper and lower clamping means apertured to expose an area of the work to the action of the stitch-forming mechanism, a needle-throat member disposed when in sewing position in the aperture of the lower clamping means, buttonhole cutting mechanism, means for relatively moving the work-clamp and needle-throat member out of sewing relation to expose the work to the action of the buttonhole cutting mechanism, said lower clamping means having a needle-throat clearance opening leading from said work-exposing aperture to permit of said relative movement, auxiliary lower work-clamping means displaceably disposed in said opening, and means actuated by the buttonhole cutting mechanism for displacing said lower auxiliary work-clamping means from work-clamping position in said opening.

7. A work-clamp for sewing machines having lower clamping plates and upper clamping feet apertured to expose an area of the work clamped between them, said lower clamping plates having an opening leading from the work-exposing aperture therein, and auxiliary lower work-clamping means disposed in said opening in cooperative relation with said upper clamping feet and shiftable relatively to said lower clamping plates out of such cooperative relation.

8. A work-clamp for sewing machines having lower clamping plates and upper clamping feet, the lower clamping plates having a sewing aperture and a clearance opening leading from said aperture, and levers pivotally mounted on said clamping plates and having clamping portions disposed in said clearance opening in work-clamping relation with said upper clamping feet, said levers being shiftable to displace said clamping portions from such work-clamping relation.

9. A sewing machine of the buttonhole type having, in combination, stitch-forming mechanism, a work-clamp having coacting upper and lower clamping means apertured to expose an area of the work to the action of the stitch-forming mechanism, a needle-throat member disposed, when in sewing position, in the aperture of the lower clamping means, buttonhole cutting mechanism, means for relatively moving the work-clamp and needle-throat member out of sewing relation to expose the work to the action of the buttonhole cutting mechanism, said lower clamping means having a needle-throat clearance opening leading from said work-exposing aperture to permit of said relative movement, and auxiliary lower work-clamping means displaceably disposed in said opening, said auxiliary lower work-clamping means comprising a pair of spring-pressed levers having their work-clamping extremities disposed adjacent the needle-throat member and formed with inclined edge portions engageable by the needle-throat member for spreading such levers during the relative movement of the work-clamp and needle-throat member out of sewing relation.

In testimony whereof, I have signed my name to this specification.

EDWARD B. ALLEN.
